UNITED STATES PATENT OFFICE.

HARRY W. YOUNG, OF CHICAGO, ILLINOIS.

ELECTRICAL FUSE.

1,235,178.

Specification of Letters Patent. Patented July 31, 1917.

Application filed January 12, 1915. Serial No. 1,791.

To all whom it may concern:

Be it known that I, HARRY W. YOUNG, a citizen of the United States, and a resident of the city of Chicago, county of Cook, and State of Illinois, have invented certain new and useful Improvements in Electrical Fuses, of which the following is a specification.

My invention relates to improvements in fuse members, and has for its object, the provision of an improved construction of this character arranged to afford a good electrical connection and tight closure.

The invention consists in the combinations and arrangements of parts hereinafter described and claimed.

The invention will be best understood by reference to the accompanying drawing forming a part of this specification, and in which,

Figure 1 is a side view shown partially in section of a fuse embodying my invention,

Fig. 2, a section taken on line 2—2 of Fig. 1,

Fig. 3, an enlarged end view of the fuse shown partially in section,

Fig. 4, an enlarged section taken on line 4—4 of Fig. 3,

Fig. 5, an enlarged section taken on line 30 5—5 of Fig. 1,

Fig. 6, a perspective view of a metallic band employed in the construction, and

Fig. 7, a perspective view of a closure plate employed in the construction.

The preferred form of construction, as illustrated in the drawing comprises an outer tube 8 of insulating material and closed at one end by means of a metallic cap 9. A screw 10 is swiveled in cap 9, as indicated and a screw 11 is slidably mounted in an inwardly opening recess 12 formed in the outer end of cap 9, as shown. A tubular fuse cartridge 13 is arranged in tube 8 and has one end closed by means of a metallic plug 14 provided with threaded sockets adapted to receive screws 10 and 11, said cartridge containing a fusible member 15 of any usual or desired form, and having one end connected with plug 14. By this arrangement, the plug 14 may be drawn into tight engagement with the cap 9 and good electrical connection afforded therewith through the medium of the two screws 10 and 11. By mounting screw 11 so as to have longitudinal sliding movement, said screw may be withdrawn until its enlarged inner end rests in re-

cess 12 and screw 10 tightened in place, whereupon screw 11 may also be tightened, thus effecting a good electrical connection. Thus the advantages of a double screw connection may be maintained and both screws permanently mounted in the device to prevent removal or misplacement thereof. By swiveling one of the screws and mounting the other for longitudinal movement the swiveled screw may be readily and completely tightened without interference from the other screw, whereupon said other screw may in turn be tightened.

A metallic band 16 is arranged over the opposite end of tube 8 to project slightly beyond the end of said tube, and is provided at one side with an inwardly extending flange 17, as shown. On its other side, band 16 is provided with inwardly off-set portions 18 and a notch 19, as shown in Fig. 6. A closure plate is arranged to fit within the end of band 16 with one side resting under flange 17, said plate being provided with a lip 21 projecting through notch 19 and overlapping the band 16. Lip 21 is provided with a screw 22 swiveled therein and the band 16 and tube 8 are provided with a threaded opening adapted to receive said screw. Plate 20 is also provided with flanges 20 adapted to fit the spaces formed by the inwardly off-set portions 18, thus effecting a tight seal and closure for the end of tube 8. The corresponding end of fuse cartridge 13 is closed by a metallic plate 23 and the corresponding end 24 of fusible member 15 is passed through said plate turned outwardly and backwardly to lie between lip 21 and band 16, said end 24 being provided with an opening to permit the passage of screw 22 so as to afford good electrical connection with the end of fusible member 15. This arrangement furnishes a tight closure and seal for the end of tube 8 and also affords good electrical connection with fusible member 15. By swiveling the heads of the screws, the separation of the screw heads from their cooperating parts is prevented so that surreptitious insertion of fusible members thereunder is prevented.

The outer tube 8 is provided at one side with an inwardly extending projection 25 and the cartridge 13 is provided with a recess 26 adapted to receive said projection so as to permit insertion of said cartridge in tube 8. This arrangement insures the proper positioning of the cartridge for engagement by

screws 10 and 11, and by arranging the projection and depression in different positions for fuses of different capacities, the misuse of the fuses will be prevented.

5 While I have illustrated and described the preferred form of construction for carrying my invention into effect, this is capable of variation and modification without departing from the spirit of the invention. I, 10 therefore, do not wish to be limited to the precise details of construction set forth, but desire to avail myself of such variations and modifications as come within the scope of the appended claims.

15 Having described my invention what I claim as new and desire to secure by Letters Patent is:

1. A fuse comprising a tube; a metallic band around one end of said tube, said band 20 being provided at one side with a projection extending partly across the end of said tube; a closure plate arranged to fit under said projection and provided with means for securing it to said band; a fusible member in 25 said tube electrically connected at the corresponding end with said band; and means for effecting electrical connection with the other end of said fusible member, substantially as described.

30 2. A fuse comprising a tube; a metallic band around one end of said tube, said band being provided at one side with a projection extending partly across the end of said tube;

a closure plate arranged to fit under said projection; a lip on said plate fitting against 35 the side of said band; a screw on said lip engaging said band; a fusible member in said tube electrically connected at the corresponding end with said band; and means for effecting electrical connection with the other 40 end of said fusible member, substantially as described.

3. A fuse comprising a tube; a metallic band around one end of said tube, said band being provided at one side with a projection 45 extending partly across the end of said tube, the other side of said band being inwardly offset and notched; a closure plate arranged to fit under said projection; a lip on said plate passing through said notch and 50 fitting against the side of said band; a screw on said lip engaging said band; flanges on said plate fitting the space formed by said inwardly offset portions; a fusible member in said tube electrically connected at the corresponding end with said band; and means for effecting electrical connection with the other 55 end of said fusible member, substantially as described.

In testimony whereof I have signed my 60 name to this specification in the presence of two subscribing witnesses.

HARRY W. YOUNG.
